UNITED STATES PATENT OFFICE.

WILLIAM M. SMITH, OF HAMPTON, VIRGINIA.

DESIGN FOR A HAT-RACK.

SPECIFICATION forming part of Design No. 24,425, dated June 25, 1895.

Application filed March 15, 1895. Serial No. 541,940. Term of patent 14 years.

To all whom it may concern:

Be it known that I, WILLIAM M. SMITH, a citizen of the United States, residing at Hampton, in the county of Elizabeth City, State of Virginia, have invented and produced a new and original Design for Hat-Racks; and I do hereby declare the following to be a clear and exact description of the same, reference being had to the accompanying drawing, forming a part of the same, and to the letters of reference marked thereon.

From the accompanying drawing it will be seen that the characteristic features of the invention consist of the two uprights or side

pieces lettered A in the drawing representing trees, having branches B and a base portion D on which the side pieces rest. Connecting the two side pieces are cross bars C C, representing branches of trees, constituting with the side pieces a frame for a mirror.

Having thus described my invention, what I claim as new is—

The design for a hat rack herein shown and described.

WILLIAM M. SMITH.
